UNITED STATES PATENT OFFICE.

WILLIAM H. GERNS, OF EAST ORANGE, NEW JERSEY, ASSIGNOR TO BRANDES LABORATORIES, INC., OF NEWARK, NEW JERSEY, A CORPORATION OF NEW JERSEY.

ELECTROMAGNETIC SOUND REPRODUCER.

Application filed December 11, 1925. Serial No. 74,802.

My invention relates broadly to electromagnetic sound reproducers and more particularly to a construction of loud speaker for use in radio reproduction.

5 One of the objects of my invention is to provide a construction of loud speaker radio reproducer having a minimum number of mechanical parts assembled in a manner which permits quantity production inexpensively and which provides an efficient form 10 of electromagnetic sound reproducer for use in radio broadcast reception.

Another object of my invention is to provide a construction of loud speaker radio 15 reproducer in which a single casting is provided for supporting a sound amplifying horn and an electromagnetic driver for actuating a sound reproducing diaphragm positioned immediately below the sound amplifying horn.

Still another object of my invention is to provide a construction of loud speaker in 20 which a single casting is provided with oppositely extending cylindrical portions, one of which serves as a support for a sound amplifying horn and the other of which serves as a support for an electromagnetic driving apparatus actuating a diaphragm positioned intermediate the extended cylindrical portions.

30 A further object of my invention is to provide a single casting for supporting a sound amplifying horn and an electromagnetic driving apparatus with means for adjustably positioning the electromagnetic driving apparatus with respect to a sound reproducing diaphragm for selecting the magnetic gap between the sound reproducing diaphragm and the electromagnetic driving apparatus for the desired tone quality of the reproduced sound.

40 A still further object of my invention is to provide a loud speaker construction with an adjustable electromagnetic driver therein with means operative from the exterior of the loud speaker and rotatable in engagement with the support for the electromagnetic driver for adjusting the magnetic gap between the electromagnetic driver and a sound reproducing diaphragm with means for limiting the movement of the electromagnetic driver in the direction of the sound reproducing diaphragm.

50 Still other objects of my invention relate to the construction and assembly of a loud

speaker mechanism in which a single casting is arranged with a lateral apertured partition between oppositely extending cylindrical portions which serve to support a sound amplifying horn and an electromagnetic driving mechanism respectively, with means screw threaded into the cylindrical portion of the casting which houses the electromagnetic driver for supporting a sound reproducing diaphragm with respect to which the electromagnetic driver is readily adjustable for varying the magnetic gap between the diaphragm and the electromagnetic driver.

60 Other and further objects of my invention will appear hereinafter as the following specification progresses and will be understood by reference to the accompanying drawings, in which:

70 Figure 1 is a side elevation partially broken away and illustrated in cross-section showing the assembly of parts of the electromagnetic sound reproducer construction of my invention; and Fig. 2 is a plan view looking beneath the base of the loud speaker 80 construction.

75 Referring to the drawings in detail, reference character 1 represents the single casting which supports all of the parts of the loud speaker construction. The casting 1 has an upwardly extending cylindrical portion 2 and a downwardly depending cylindrical portion 3 with an intermediate partition separating the cylindrical portions as 85 represented at 4. The partition 4 is apertured at 5 for the delivery of sound vibrations to a sound amplifying horn supported in the cylindrical portion 2. The casting 1 is provided with an annular depending flange 6 immediately below the cylindrical portion 2 which flange cooperates with a corresponding flange 10 upon a screw threaded ring member 7 to support the sound reproducing diaphragm 9. The depending cylindrical portion 3 is interiorly screw threaded to receive the ring member 7 and to receive the screw threaded supporting plate 12 which carries the electromagnetic driver. The screw threaded supporting plate 12 is provided with an upwardly extending screw 90 threaded wall 11 which engages with the interior screw threads on the cylindrical portion 3. A rubber ring member 8 circular in cross-section is interposed between the upper extremity of the supporting plate 12 and the 105 110

lower face of the screw threaded ring member 7 forming a cushion against which the supporting plate 12 may be adjusted to vary the size of the magnetic gap between the 5 electromagnets 15 and the diaphragm 9. The electromagnetic driver comprises a pair of electromagnets shown in elevation at 15 and the permanent magnet system 16. A central screw member 18 is provided in the 10 supporting plate 12 from which an angularly adjustable lever 19 projects. The lever 19 depends downwardly at 17 and is directed radially and then upwardly as represented at 20 being prevented from completing 15 a 360° movement by abutment with the downwardly depending shaft member 21. The shaft member 21 is journaled in the casting 1 as represented at 22 and may be rotated under control of hand knob 23. A pinion 24 is carried on the lower extremity of the shaft member 21 and meshes with the teeth 14 formed on the peripheral edge of the supporting plate 12.

The lever 19 forms a limiting stop against 25 the movement of the electromagnets 15 in the direction of diaphragm 9. The adjusting screw 23 is prevented from revolving to a position where the electromagnets 15 abut against the surface of the diaphragm 9 by virtue of a selected setting of the stop lever 19 which prevents the upward travel of the electromagnets 15 beyond a predetermined and extremely small magnetic leakage gap. Rotation of the adjusting knob 23 in an opposite direction to its final upward limit direction serves to retract the electromagnets 30 15 from the diaphragm 9 thereby enlarging the magnetic leakage gap. This process results in deformation of the resilient ring member 8, at all times establishing a tensioned position of ring member 7 and supporting plate 12 in the threads of the depending cylindrical portion 3. The rapid vibrations to which the electromagnetic 35 driving mechanism is subjected requires that all parts be assembled in such manner that the tendency to chatter is eliminated and I find that the construction of my invention accomplishes this purpose.

In the assembly of the loud speaker, the base member 1 is inverted and the diaphragm 9 seated on the annular flange 6. The ring member 7 is screw threaded into the cylindrical portion 3 gripping the lower 50 surface of diaphragm 9 by means of annular flange 10. The deformable gasket 8 is next placed in position and the electromagnetic driver is then screwed into place. The screw member 18 is loosened to enable the top lever 19 to be screwed in position at 55 which movement of the electromagnets 15 is prevented beyond a desired limit, after which the desired adjustment may be obtained by a retracting movement of the supporting plate 12 substantially through 360°.

The construction of my invention described herein has been found to be extremely practical in quantity production and efficient in its electrical operation. While I have described my invention in certain preferred embodiments, I desire that it be understood that modifications may be made and that no limitations upon the invention are intended other than those imposed by the scope of the appended claims.

What I claim and desire to secure by Letters Patent of the United States is as follows:

1. An electromagnetic sound reproducer comprising in combination a base, a pair of cylindrical portions cast integral with said base, one of said portions extending vertically and serving as a support for a sound amplifying horn and the other of said portions depending downwardly and arranged to receive an adjustable electromagnetic driving apparatus therein, an apertured partition member separating said portions, a sound reproducing diaphragm supported below said partition member and adapted to be actuated by said electromagnetic driving apparatus, a rotatable actuator extending upwardly through said base and operative from the exterior thereof, a pinion on said actuator arranged to engage with teeth positioned around the periphery of said electromagnetic driving apparatus for adjusting the magnetic gap between said electromagnetic driving apparatus and said sound reproducing diaphragm.

2. An electromagnetic sound reproducer comprising in combination a base member, having a pair of cylindrical portions cast integral therewith, with one of said portions extending upwardly and serving as a support for a sound amplifying horn and the other of said portions depending downwardly and serving to receive a rotatable plate member carrying an electromagnetic driving apparatus thereon, a sound reproducing diaphragm carried in the upper extremity of said last mentioned cylindrical portion, a rotatable actuator journaled in said base member and operative from the exterior thereof, a pinion carried by said rotatable actuator and arranged to mesh with teeth formed on the peripheral edge of said rotatable plate member for advancing or retracting said electromagnetic driving apparatus with respect to said sound reproducing diaphragm for varying the magnetic gap therebetween.

3. An electromagnetic sound reproducer comprising in combination a base member having a pair of cylindrical portions cast integral therewith, with one of said portions extending upwardly and serving as a support for a sound amplifying horn and the other of said portions depending downwardly and serving to receive a rotatable

plate member carrying an electromagnetic driving apparatus thereon, a sound reproducing diaphragm carried in the upper extremity of said last mentioned cylindrical portion, a rotatable actuator journaled in said base member, said rotatable actuator being operative from the exterior of said base member and having its lower end projecting downwardly in a line substantially at right angles to the plane of said rotatable plate member, a pinion carried by said rotatable actuator and arranged to mesh with teeth formed on the peripheral edge of said rotatable plate member, a screw device centrally positioned in said rotatable plate member and having a radially extending lever secured thereon, said lever projecting beyond said rotatable actuator and arranged to abut with the downwardly depending end of said actuator forming a limit stop to prevent the movement of said electromagnetic driving apparatus beyond a predetermined magnetic gap with respect to said sound amplifying diaphragm, while permitting the adjustment of said magnetic gap to a larger predetermined size upon rotation of said rotatable actuator.

4. An electromagnetic sound reproducer comprising in combination a base member, a support for a sound reproducing dia-

phragm carried by said base member, an electromagnetic driving apparatus, a rotatable plate member for supporting said electromagnetic driving apparatus, said rotatable plate member being screw 35 threaded into said base member to enable said electromagnetic driving apparatus to be advanced or retracted from said sound reproducing diaphragm, a rotatable actuator extending through said base member and having a pinion thereon arranged to mesh with teeth formed on the peripheral edge of said rotatable plate member, a radial lever centrally secured to said rotatable plate member and angularly adjustable 40 about said plate member, said lever projecting beyond said rotatable actuator and forming an abutment therewith, whereby said lever may be adjusted to a particular angular position in abutment with said actuator for limiting the movement of said electromagnetic driving apparatus in the direction of said sound reproducing diaphragm, while permitting the enlargement 45 of the magnetic gap between said sound reproducing diaphragm and said electromagnetic driving apparatus through a distance substantially equal to 360° rotation of said rotatable plate member.

WILLIAM H. GERNS.
